LAUNDRY APPARATUS

Joseph Pelensky, Philadelphia, Pa., assignor to Philco Corporation, Philadelphia, Pa., a corporation of Delaware
Filed Mar. 2, 1962, Ser. No. 177,038
17 Claims. (Cl. 68—18)

This invention relates to laundry apparatus, and more particularly to laundry apparatus utilizing wobble-type agitators.

In laundry machines generally, it is the practice to achieve washing by imparting vigorous movements to the articles being laundered. In "wobble-type" laundry machines, the washing action is accomplished by freely journaling an agitator of suitable configuration on an obliquely disposed member, such as an inclined portion of a rotatable drive shaft, the agitator being prevented from rotating with respect to the tub by suitable restraining means. Continuous unidirectional rotation of the drive shaft, acting through the eccentric inclined shaft portion, imparts a nonrotational undulatory or wobbling motion to the agitator, producing circulation of the wash fluid and causing articles being washed to be brought into intimate contact with the turbulent streams of water generated by movement of the agitator.

It is an objective of the present invention to provide improved wobble-type agitator structure.

It is a further objective of the invention to provide an improved combination of a stationary column and wobble-type agitator apparatus through which the number of linkages and seals may be reduced, and which combination achieves an optimum washing action.

It is a further object of the invention to provide improved means for achieving rotation free undulatory movements of a wobble-plate agitator.

It is a still further object of the invention to provide improved agitator means for creating turbulent streams of wash fluid effective both to wash clothes and to accommodate a filtering action for the wash fluid.

In achievement of the foregoing and other objectives, the invention, in a preferred embodiment thereof, comprises a wobble-plate agitator supported by spider bracket means affixed to a suitable bearing mounted upon inclined shaft means extending into the tub and spin basket of a washing machine. Hollow, generally cylindrical column means is supported concentrically with the tub and basket by bracket means comprising a shroud affixed to the basket and including circumferentially spaced apertures through which arms of the spider bracket means extend, in interdigitating relation therewith. The construction and arrangement is such that arms of the agitator support bracket means may undulate within the apertures of the shroud. The apertures within the shroud advantageously accommodate unidirectional flow of wash fluid downwardly through the hollow column and the shroud and outwardly therefrom through the apertures, which unidirectional flow is created through the novel cooperative action of the shroud and means including an impeller disposed within the latter and movable with the spider bracket means. Conveniently, suitable strainer means is provided in the upper region of the shroud whereby positive filtering of the unidirectionally flowing wash fluid is achieved.

In further accordance with the invention the agitator comprises a main hollow cylindrical body portion concentric with the spider bracket means, said body portion including: an upper flexible sleeve portion affixed to the column; a flange adjacent thereto extending transversely of said body portion; a plurality of flipper means extending transversely of said body portion and disposed adjacent the lower portion of the latter; and an undulatory

2

flexible flange extending outwardly from said body portion in a region intermediate said upper flange and said flipper means, peaks of said undulatory flange being disposed above said flipper means and dips thereof being disposed intermediate said flipper means.

It is a feature of the invention that the flow of fluid through the hollow shroud not only accommodates a filtering action but also prevents fabrics from becoming lodged beneath the agitator and hindering its washing action.

For a better understanding of the foregoing, as well as other objects and features of the invention, reference may be had to the following description taken in light of the accompanying drawing, in which:

FIGURE 1 is a perspective showing of a laundry machine embodying the invention and with parts broken away;

FIGURE 2 is an enlarged elevational view of the machine illustrated in FIGURE 1, partly in section and with parts broken away;

FIGURE 3 is a sectional view of apparatus shown in FIGURE 2, looking generally in the direction of arrows 3—3 applied thereto and showing additional features of the invention; and

FIGURE 4 is an enlarged sectional showing, with parts removed, illustrating apparatus seen in FIGURE 2.

With more particular reference to the drawing, and first to FIGURES 1 and 2, the invention is embodied in a washing machine of the type including a cabinet 10 having a top wall 11 provided with an access opening 12, and a door 13 hingedly mounted over the opening. Means for controlling the machine comprises a control element mounted upon an escutcheon plate 16.

An upwardly presented tub 17 is housed within cabinet 35 10, and is supported upon a tubular column 21 that is resiliently mounted upon suitable base means (not shown) forming part of the cabinet. There is also housed within the cabinet suitable motor and transmission means, such for example as is disclosed and claimed in my copending 40 disclosure entitled "Drive Mechanism," filed December 26, 1961, bearing Serial No. 161,962, and assigned to the assignee of the present invention. The relation which the motor and transmission means bear to the invention, while not necessary to an understanding thereof, will be 45 discussed briefly later in this description.

An upwardly presented rotatable basket 22 is nested coaxially within tub 17 and supported upon hub means 50 23 journalled within bearing means 24 provided in the bottom of non-rotatable tub 17, in the region of the upper end of column 21. A hollow shaft 25 extends downwardly from hub means 23 concentrically with column 21, and is connected to the output drive of the transmission which provides high speed spin of basket 22. A solid shaft 26 is disposed concentrically with hollow shaft 25. Shaft 26 is journalled by bearing means 55 27 for rotation within hub means 23 and its extension 25, and is adapted to be rotated by the output drive of the transmission providing for operation of the agitator 31 which will be described in detail in what follows.

With reference also to FIGURE 4, the upper end of shaft 26 includes an inclined portion 32, and base 33 for agitator 31 is journalled to the inclined shaft portion by bearing means 34 which is coaxial with the latter.

An annular face seal 28 is mounted coaxially upon the bottom of tub 17 and seals against an annular sealing member 29 provided in hub means 23.

More particularly, the inclined shaft portion 32 comprises a pair of sleeves 41 and 42 carried by agitator shaft 26. Sleeves 41 and 42 comprise axially aligned portions 43 and 44, respectively. The axis along which portions 43 and 44 are aligned is disposed with angularity as respects the axis of the agitator shaft. The inner

race of bearing means 34 is mounted upon portions 43 and 44 and is held in place by shoulders 45 and 46 thereof, through a clamping force exerted by the latter elements upon the inner race. This clamping force is provided by a nut 48 threaded onto the upper end of agitator shaft 26 and forcibly engaging upper sleeve 43. The outer race of bearing 34 is confined within the cup shaped hub portion 47 of agitator base 33.

With reference also to FIGURE 3, base 33 includes a spider of three arms 51 spaced 120° apart and extending radially from hub portion 47. Arms 51 extend with clearance through apertures 53 provided in bracket means comprising a generally cylindrical shroud 52 mounted concentrically with the bottom of basket 22 by screws. The apertures 53 divide the shroud into generally vertically extending tripod leg or support portions disposed in interdigitating relation with arms 51. Shroud 52 tapers somewhat at its upper end to a lesser diameter cylindrical portion 54.

As seen in FIGURES 1 and 2, a generally cylindrical wash aid dispenser 55 is mounted upon the lesser diameter portion 54 of shroud 52 and includes a lint screen 56 in the lower portion thereof, and in the upper region of the shroud. Additional structural details of the dispenser 55 will not be described, inasmuch as such details are not necessary to an understanding of the invention. It should be mentioned, however, that the side wall of dispenser 55 includes slots 57 and the bottom is open, whereby wash fluid may flow, sequentially, through slots 57, screen 56, and the open bottom of the dispenser. These and other features of a dispenser of this kind may be more fully understood by making reference to my U.S. Patent No. 2,982,120, entitled "Laundry Aid Dispensing Means for Clothes Washing Machines," and assigned to the assignee of the present invention.

As is seen in FIGURES 2 and 3, mounting of the agitator 31 upon arms 51 is made by means of a rigid cylindrical liner 61 to which the main body portion 65 of the flexible and resilient agitator vanes is adherent. Liner 61 includes open-ended grooves 62 within which end portions 63 of arms 51 are received. Mounting is maintained by screws 64 that extend through agitator 31, liner 61, and into threaded engagement with ends 63 of arms 51.

As best seen in FIGURES 1 and 2, agitator 31 comprises a main cylindrical body portion 65, this being the above described portion closely engaging liner 61. A flattened ring or flange portion 66 extends outwardly from the upper region of agitator body portion 65, and an undular flange portion 67 extends outwardly from portion 65 and has much the shape of the brim of an inverted "three-cornered" hat (see FIGURE 1). Beneath each of the "peaks" of flange 67 there is disposed a flipper or vane 68 (see also FIGURE 3) that extends radially from the lower edge of agitator body portion 65. The lower edge of agitator portion 65 includes a bead 71 that extends slightly inwardly and over the lower rim of liner 61, and assists in maintaining attachment of the agitator to its liner.

Agitator 31 further includes a sleeve portion 72 that extends upwardly from upper flange 66. Agitator portion 72 includes a bead portion 73 that is clamped between a lower rim portion of dispenser 55 and an upper rim portion of shroud 52. A bellows-like flexible and resilient sleeve 58 is provided to seal the eccentric mechanism. Sleeve 58 is clamped by screws between basket 22 and its hub 23, at one end, and by screws between the portion of agitator base 33 mounted on bearing 34 and its spider hub portion 47, at the other end.

The upper clamped region of sleeve 58 comprises a circumferential annular flange or vane 59 that extends radially from the sleeve and toward shroud 52. Vane 59 includes tab portions 60 that are disposed for movements within the slot-like apertures 53, as agitator base 33 is caused to undulate. A similar, but rigid and perforate,

circumferential annular flange 38 extends radially from hub portion 47 of agitator base 33, and closely overlies vane 59. The novel function of this vane and flange structure will be set forth later in the description.

Unlike certain prior mechanisms, the sealing sleeve 58 is not relied on to prevent rotation of the agitator with respect to the basket. This function is performed by three pins 35 that are spaced 120° apart, and which extend into apertures 36 and 37 provided in hub means 23 and in agitator base 33, respectively. For the sake of convenience, only one of pins 35 is shown. Each pin is mounted securely within an aperture 36 and extends with some clearance into an aperture 37. Each of apertures 37 comprises a generally cylindrical bore that is slightly flared from its central region toward its upper and lower ends. The flaring accommodates substantially continuous engagement of the walls of each aperture 37 with an inserted pin 35 as the agitator base 33 wobbles during the washing operation, which pins also relieve sleeve 58 from relative twisting forces between agitator 31 and basket 22.

In the operation of the above described apparatus, continuous unidirectional rotation of shaft 26 is provided by suitable transmission means while hollow shaft 25, and basket 22 attached thereto, is held from rotating by suitable brake means. Rotation of shaft 26 effects non-rotative undulatory movements of the agitator base 33, and agitator 31 supported thereon. Rotation of agitator base relative to shroud 52 and the basket 22 is prevented by the interengagement of pins 35 with the tapered walls of apertures 37.

As the agitator 31 undulates, a generally annular current of wash fluid is created, as indicated by the arrows in FIGURE 2, by the cooperative pumping action of flange 66, undular flange 67, and flippers 68.

The fluid flows generally upward adjacent the vertical walls of basket 22 and downwardly in the region of hollow column 55 and agitator 31, as shown by the arrows appearing in FIGURE 2. A portion of the downwardly moving fluid flows through slots 57, screen 56, and outwardly through slots 53 in shroud 52, after which it is forced vigorously outwardly by flippers 68 disposed in the regions of the slots. Propulsion of the fluid through the interior of shroud 52 is advantageously enhanced by the undulatory movements of vane 59 and flange 38. In undulating, downward movements of vane 59 impel the fluid downwardly, and flange 38 engages the upper surface of the vane to rigidify the latter in its downward, fluid-pumping movement. In moving upwardly, vane 59 is deflected downwardly by the relative force of the fluid, thereby flexing away from flange 38, and the liquid passes outboard of the edge of the vane and also through the perforations in flange 38. This condition creates little or no downward pumping action so that, at most, the fluid inside the shroud will cease to flow. Since, however, undulatory movements of flange 38 and vane 59 are continuous, the net effect is a steady flow of fluid downwardly through the screen, interiorly of the shroud, and outwardly through the apertures.

Another portion of the downwardly moving wash fluid flows downwardly over the flanges 66 and 67 and rejoins the flipper-directed fluid. This lower, horizontal fluid current flow is further assisted by the dip portions of flange 67, such horizontal flow preventing clothes from becoming lodged beneath the agitator 31.

It will be appreciated that the invention provides an improved combination of a stationary column and wobble-type agitator apparatus by virtue of which the number of linkages and seals are reduced and which combination achieves an optimum washing action. The invention also provides improved wobble type agitator means which creates turbulent streams of wash fluid effective both to wash clothes and to accommodate a filtering action for the wash fluid.

While but a single preferred embodiment of the inven-

tion has been illustrated and described, it will be understood that modifications are contemplated by the scope of the appended claims.

I claim:

1. In a laundry machine, the combination comprising: basket means within which may be disposed clothes to be washed; bracket means including generally vertically extending support members spaced from one another and mounted within said basket means, and including an open central portion generally concentric with the axis of said basket means, through which portion wash fluid may flow; hollow column means extending generally coaxially with said open central portion of said bracket means and having apertures through which wash fluid may flow; screen means extending transversely of said column means and disposed at a level below the level of said apertures of said column means; hub means disposed and adapted for undulatory movements within said basket means, including radially extending arms disposed in interdigitating relation with said vertically extending members of said bracket means; and agitator vane means mounted for movement by said hub means and said arms, the construction and arrangement being such that undulatory movement of said agitator vane means effects flow of wash fluid inwardly through apertures of said column means, downwardly through said screen means and through said open central portion of said bracket means, thence outwardly from beneath said agitator means.

2. A laundry machine in accordance with claim 1 and further including a flexible annular flange structure moving with said hub means and disposed and adapted to enhance the downward flow of wash fluid by inhibiting retrograde upward flow of the wash fluid through said bracket means.

3. The combination according to claim 1, and further characterized in that said bracket means comprises a generally cylindrical member having apertures and said arms extend through said apertures, said cylindrical member having its base portion affixed to said basket means.

4. The combination according to claim 1, and further characterized in that said vane means comprise: a generally cylindrical body portion supported by said radially extending arms and substantially enclosing said bracket means; and a flexible and resilient undular flange extending radially from surface portions of said body portion.

5. The combination according to claim 4, and further characterized in that said vane means includes radially extending vanes disposed below the peaks of said undular flange, the construction and arrangement being such that upon undulatory movements of said agitator vane means, wash fluid within said basket is caused to be pumped, by the cooperative action of said vane means and said column, through said screen in the region of the central opening of said bracket means and column and outwardly through spaces between members of said bracket means.

6. In a laundry machine, the combination comprising: basket means within which may be disposed clothes to be washed; bracket means within said basket means, including an open central portion generally concentric with the axis of said basket means and leg portions mounting said bracket means to said basket means; hollow column means extending generally coaxially with said open central portion of said bracket means and having apertures through which wash fluid may flow; screen means extending transversely of said column means and disposed at a level below the level of said apertures of said column means; hub means disposed and adapted for undulatory movements within said basket means, including radially extending arms disposed in interdigitating relation with leg portions of said bracket means; and an agitator including vane means extending from said hub and mounted for movements by said hub, the construction and arrangement being such that undulatory movement of said agitator and vane means effects flow of wash fluid inwardly through apertures of said column means, downwardly through said

screen means and through said open central portion of said bracket means, thence outwardly from beneath said agitator means.

7. In a laundry machine, the combination comprising: basket means within which may be disposed clothes to be washed; bracket means comprising a hollow generally cylindrical member generally concentric with the axis of said basket means and having a plurality of apertures in the walls thereof; hollow column means extending generally coaxially with said open central portion of said bracket means and having apertures through which wash fluid may flow; hub means disposed and adapted for undulatory movements within said basket means, including radially presented arms extending through the apertures of said bracket means; and an agitator including vane means extending from and moving with said hub means and said arms, the construction and arrangement being such that undulatory movements of said agitator vane means effects flow of wash fluid inwardly through apertures of said column means, downwardly through the open central portion of said cylindrical bracket means, thence outwardly through apertures thereof and from beneath said agitator means.

8. The combination according to claim 7 and further characterized in that said vane means comprise: a generally cylindrical body portion supported by said radially presented arms and substantially enclosing said bracket means; and a flexible and resilient undular flange extending radially from surface portions of said body portion.

9. The combination according to claim 8 and further characterized by the inclusion of: a perforate, radially presented rigid flange extending about the periphery of said hub means; and a radially presented, imperforate flexible and resilient flange disposed beneath said perforate flange and extending beyond the outer periphery of the latter while spaced from the cylindrical wall portion of said bracket means, the construction and arrangement being such that said flexible and resilient flange upon moving downwardly is engaged by the perforate flange and prevented from flexing whereby to impel water downwardly through said open central portion of the bracket means, and upon moving upwardly said imperforate flange is disengaged by said perforate flange and is flexed downwardly by the fluid and permits the latter to flow past.

10. In a laundry machine, wobble type agitator means comprising: an agitator base comprising radially presented arms; generally cylindrical shroud means having apertures through which said arms extend; a generally cylindrical member generally concentric with said base, supported by said arms, and disposed about said shroud means; vane means supported by said cylindrical member; and eccentric means coupled with said agitator base and operative to impart undulatory movements to the latter, the construction and arrangement being such that wash fluid is caused to flow downwardly through said shroud means, outwardly through said apertures, and from beneath said cylindrical member.

11. A laundry machine in accordance with claim 10, and further including a flexible annular flange structure moving with said eccentric means and disposed and adapted to enhance the downward flow of wash fluid by inhibiting retrograde upward flow of the wash fluid through said shroud means.

12. Agitator means according to claim 10, and further characterized in that said vane means comprises: a radially presented flange extending along an upper peripheral portion of said cylindrical member; an undular, radially presented flange extending from a peripheral region of said member below said flange; a plurality of radially presented flippers, each disposed beneath and spaced from a peak of said undular flange; and flange means extending radially from said agitator base toward inner surface portions of said shroud means, and adapted to impel wash fluid solely downwardly upon undulatory movements of said base means.

13. The combination according to claim 12, and fur-

ther including: hollow column means, including slotted wall portions concentrically supported upon said shroud means; and screen means extending transversely of said column means in a region below said slotted wall portions, said screen means being adapted to strain wash fluid as it flows downwardly into said shroud means.

14. In a clothes washing machine the combination comprising: a basket; a generally cylindrical agitator having an open upper portion, a generally vertically extending cylindrical main body portion, the lower portion of which main body portion is spaced above the bottom of said basket, undulatory vane means extending radially from peripheral portions of said main body portion, and a plurality of flipper means each disposed below and spaced from a peak of said undulatory vane means; and means for moving the agitator to undulate the same and effect a washing action, the construction and arrangement being such that disposition of said flippers relative to said basket as they move is such as to create an outward pumping action between adjacent portions of the agitator main body portion and the basket.

15. The combination according to claim 14 and further characterized in that said means for moving the agitator to effect a washing action comprises: unidirectionally rotatable shaft means extending into the main body portion of said agitator; a pair of axially spaced sleeves supported upon said shaft and including axially aligned surface portions concentric with an axis disposed with angularity as respects the agitator shaft; bearing means supported coaxially with said angularly disposed surface portions of said sleeves; agitator support means carried by said bearing means and including a plurality of arms extending radially from the latter, said arms

disposed in supporting engagement with said main body portion of said agitator; and shroud means concentric with said basket, spaced inwardly from said agitator body portion and including apertures through which said radially presented arms extend.

16. An agitator assembly adapted to be immersed in a body of wash fluid and oscillatably moved therein to impart vigorous movements to the fluid and to articles to be washed within said fluid, said assembly comprising: 10 a hollow, generally cylindrical main body portion adapted to provide for support of said agitator assembly; undulatory flexible vane means extending radially from peripheral regions of said main body portion; a plurality of flexible vane means extending radially from peripheral regions of said body portion, each disposed below and spaced vertically from a peak region of said undulatory vane means; a flexible concentric sleeve portion extending from an upper region of said generally cylindrical main body portion; and an annular flexible 20 flange extending radially from a region of said main body portion above said undulatory vane means and spaced from the latter.

17. Agitator assembly according to claim 16 and further including a relatively rigid, cylindrical liner adapted to provide for support of the agitator assembly and frictionally engaging interior regions of said main body portion.
